[57] **CLAIM**

The ornamental design for a hand-held vegetation trimmer, as shown and described.

DESCRIPTION

FIG. 1 is a front and top perspective view of a hand-held vegetation trimmer;

FIG. 2 is a rear and top perspective view;

FIG. 3 is a left side view;

FIG. 4 is a right side view;

FIG. 5 is a bottom view;

FIG. 6 is a front view;

FIG. 7 is a top view; and,

FIG. 8 is a rear view.

The broken line showing of a cutting blade and an operating button is for illustrative purposes only and forms no part of the claimed design.
